UNITED STATES PATENT OFFICE.

SAMUEL MITCHELL, OF NEW YORK, N. Y.

DESIGN FOR A RING.

56,184.

Specification for Design. Patented Aug. 24, 1920.

Application filed March 20, 1920. Serial No. 367,488. Term of patent 7 years.

To all whom it may concern:

Be it known that I, SAMUEL MITCHELL, a citizen of United States, and resident of the borough of Manhattan, in the county of New York, city and State of New York, have invented certain new, original, and ornamental Design for Rings, of which the following is a specification, reference being had to the accompanying drawing, forming part thereof.

Figure 1 is an enlarged plan view of the ring showing my new design. Fig. 2 is a perspective view of the ring.

I claim:

The ornamental design for a ring as shown.

Signed at New York city in the county of New York, and State of New York, this 18th day of March, 1920.

SAMUEL MITCHELL.
